United States Patent

Des. 235,724
Patented July 8, 1975

235,724

STORAGE CONTAINER OR THE LIKE

James B. Swett, Barrington, R.I., assignor to Dart
Industries Inc., Los Angeles, Calif.

Filed Jan. 9, 1974, Ser. No. 432,023

Term of patent 14 years

Int. Cl. D7—07; D9—02

U.S. CL. D7—79

FIG. 1.

Des. 235,724
PAGE 3

FIG. 2.

FIG. 5.

FIG. 3.

FIG. 4.

FIG. 1 is a side elevational view of a storage container or the like showing my new design;

FIG. 2 is a top plan view thereof;

FIG. 3 is a bottom plan view thereof;

FIG. 4 is a partial cross-sectional view on an enlarged scale taken on line 4-4 of FIG. 2 showing the rim configuration; and

FIG. 5 is a partial cross-sectional view on an enlarged scale taken on line 5-5 of FIG. 2 showing the base rim configuration.

I claim:

The ornamental design for a storage container or the like, substantially as shown.
